UNITED STATES PATENT OFFICE.

FRANK WELLINGTON PUTMAN, OF NEWPORT, RHODE ISLAND.

PORTABLE AND COLLAPSIBLE ARTICLE OF FURNITURE.

1,378,613.

Specification of Letters Patent. Patented May 17, 1921.

Application filed October 4, 1920. Serial No. 414,574.

To all whom it may concern:

Be it known that FRANK WELLINGTON PUTMAN, citizen of the United States, residing at Newport, in the county of Newport and State of Rhode Island, has invented certain new and useful Improvements in Portable and Collapsible Articles of Furniture, of which the following is a specification.

10 My present invention has reference to a portable article of furniture particularly, but not necessarily designed for use by automobileists, and which is of a collapsible nature whereby the same may be folded to 15 provide a small package which can be conveniently stored in the seat box or in other parts of an automobile without inconvenience to the occupants thereof.

20 My primary object is to produce a portable article of furniture which may be employed as a table, stool, or toilet seat, and in which the top thereof comprises two hinged sections whose edges abut when the sections are spread, so that both of the sections will be arranged in the same plane, 25 said top being supported by foldable legs of a novel construction which firmly brace the top when the article of furniture is set up so as to render the same rigid and stable.

30 A further object is the production of a portable collapsible article of furniture which includes a top constructed of hinged sections provided on their under faces with means for receiving the offset upper ends of 35 the supporting legs, the latter constituting each a pair of pivotally connected members, slideable means engaging one of the members of each pair of legs for bringing the lower portions thereof toward each other, to

40 add to the stability of the said legs, bringing the upper ends thereof into tighter interengagement with the receiving means on the under face of the top, and spreading the said legs to a position whereby material 45 which may pass through the center of the seat will not contact with the said legs.

The foregoing, and other objects which will appear as the nature of the invention is better understood, may be accomplished 50 by a construction, combination and operative assemblage of parts, such as is illustrated by the drawings which accompany and which form part of this application.

In the drawings:—

Figure 1 is a perspective view of the improvement in its set up position. 55

Fig. 2 is a plan view looking toward the under face of the top.

Fig. 3 is a perspective view of one pair 60 of supporting legs.

Fig. 4 is a side elevation of the improvement.

While in the drawings I have illustrated my improvement in the nature of a toilet seat, it is to be understood that the same 65 may be in the nature of a stool or table. When employed as a table, the top of the latter may be of any desired length, and the supporting means therefor, constituting the legs, may be arranged at both ends of the 70 table. Also, if desired, when the device is in the nature of a toilet seat, as shown by the drawings, the segmental top thereof 75 may be suitably covered so that the same can be thus readily converted into a stool.

Referring now to the drawings in detail, the top of my improved collapsible and convertible article of furniture is indicated by the numeral 1 and comprises two similarly formed semi-elliptical members 2—2. The 80 confronting ends of the sections or members 2 are straight and abut, when the sections are brought to parallelism, so that both of the sections will be arranged in the same plane. 85

The sections 2, on their under faces, and at their confronting ends are connected by hinges 3. This permits of the sections being folded against each other when not required for use. Each of the sections has 90 on its under face, adjacent to its ends depending eyes or sockets 4.

As disclosed by the drawings, I employ legs for supporting the top. The legs, of course, may be of any desired length, so 95 that the seat may be positioned at proper elevations to receive the occupant thereof. The legs are preferably in the nature of comparatively light metal bars of a sufficient strength to withstand the strain to 100 which they are subjected. The legs are arranged in opposed pairs, and as each pair is similarly constructed, the main members or bars of each pair of legs is indicated by the numeral 5. One of the bars 5 is arranged 105 in lapping relation with respect to the other,

and the said bars are pivotally connected together, as at 6. The pivot is preferably arranged nearer the upper ends of the legs than the lower ends thereof. The lower 5 ends are formed with offset portions providing feet 7. The feet are directed outwardly with respect to the seat. The upper ends of the bars constituting the legs are given a half twist, as at 8 and from thence 10 are continued angularly to provide tongues 9, and these tongues are designed to be received in the respective eyes or sockets 4. The bore of the eyes or sockets is rectangular as are the tongues 9, so that the said 15 tongues will frictionally engage with the walls of the said eyes or sockets.

To more effectively hold the tongues in the eyes or sockets of the top or seat 1, as well as to spread the lower ends of the said 20 legs, the opposed pairs of legs are arranged tripodal by slipping a ring 10 around the foot portions of two of the opposed legs of the respective pairs, and from thence passing the same over the bodies of the said 25 leg sections. The ring is of a size to cause the ends of the said leg sections to be brought very close together, if not in contacting engagement. This, of course, causes legs thus engaged to cause the fingers thereof to 30 slightly turn in the sockets, and to be brought into greater frictional contact with the walls of said sockets. In addition to this, the legs are effectively held against collapsing, and materially strengthened to 35 withstand strain on the seat. Still again, as above stated, the legs are spread so that material passing between the sections 2 will not contact with the said legs. The legs may be readily separated from the seat after the 40 removal of the ring 10. The legs may be folded against each other, and the sections 2 of the seat may be likewise swung against each other. Thus a comparatively small 45 bundle is provided which may be readily inserted in the seat box, or may be conveniently carried in other parts of an automobile. The construction is extremely simple, can be cheaply manufactured, may be readily set up or collapsed, is strong and durable 50 as well as thoroughly efficient for the purposes for which it is devised.

Having thus described the invention, what I claim, is:—

1. A portable article of furniture for the 55 purpose set forth, including a seat having elements on the bottom thereof, pivotally connected crossed legs having their upper ends provided with means for engaging said elements, and means engaging one of the 60 opposed legs of the respective pairs of legs for forcing said legs together at the lower portions thereof and for spreading the upper portions of both pairs of legs for locking all of the legs with the elements of the 65 seat.

2. In a portable article of furniture for the purpose set forth, a foldable seat having spaced pairs of sockets on the bottom thereof, a support for the seat comprising pairs of leg members, each pair being pivotally 70 connected together and having their upper portions formed with angle tongues and their lower portions formed with angle feet, said tongues designed to be received in the sockets of the seat, and removable means 75 engaging two of the oppositely disposed legs of the respective pairs of leg members for forcing the lower or foot portion of said legs together and spreading the upper portions of each pair of legs for retaining the 80 tongues of the legs in the sockets.

3. A portable article of furniture, for the purpose set forth, including a top comprising two sections hinged at the abutting ends thereof and designed for retaining the sections in parallelism when the said ends are brought into abutting engagement, a socket on the under face of the seat adjacent to the outer ends of each of the sections thereof, a support for the seat comprising opposed 85 pairs of legs, each pair being pivotally connected, having its outer end offset to provide a foot and its inner end twisted and extended to provide a finger that is designed to be received one in the respective sockets 90 of the seat.

4. A portable article of furniture, including a seat comprising two flat elliptical sections which are hingedly connected together and which, when their ends are in abutment 100 have their upper and lower surfaces parallel, depending sockets arranged in opposed pairs adjacent the ends of the seat, supports, comprising legs for the seat, each of said legs having flat body portions which 105 are arranged in pairs and which are pivotally connected, said body portions having their outer ends flanged to provide feet, and twisted and extended at their inner ends to provide fingers designed to be received in 110 the respective sockets, and means removably associated with two of the members of the opposed pairs of legs for bringing said legs toward each other and providing a tripodal 115 support.

5. A portable article of furniture for the purpose set forth, comprising a seat constructed of hinged sections foldable in one direction only, depending substantially rectangular sockets on the under face of the 120 seat arranged in pairs adjacent to the ends thereof, a support for the seat comprising opposed pairs of leg members, each pair of leg members being pivotally connected, having feet at the outer ends thereof and angle 125 tongues at the opposite ends, which latter are designed to be received in the respective sockets of the seat, and a ring removably connected to and slidable upon two of the opposed members of each pair of legs, where- 130

by to bring the lower ends of the said legs toward each other, as and for the purpose set forth.

6. In a portable and foldable article of furniture, a top, removable legs supporting the top disposed in opposed pairs, and means slidale on two legs of the opposed

pairs, arranging the same at an inward angle with respect to each other and locking the same together, and also causing the 10 spreading of both pairs of legs at the upper and seat receiving portions thereof.

In testimony whereof I affix my signature.
FRANK WELLINGTON PUTMAN.
